(57) **CLAIM**

The ornamental design for a tablet for displaying a plurality of holographic images, as shown and described.

DESCRIPTION

FIG. 1 is a front perspective view of a tablet for displaying a plurality of holographic images showing the new design.

FIG. 2 is a rear perspective view of the invention.

FIG. 3 is a front elevation view of the invention.

FIG. 4 is a rear elevation view of the invention with the tablet's stand in the closed position.

FIG. 5 is a top plan view of the invention.

FIG. 6 is a bottom plan view of the invention.

FIG. 7 is a left side view of the invention.

FIG. 8 is a right side view of the invention.

FIG. 9 is a right side view of the invention with the tablet's stand in the open position.

FIG. 10 is a rear perspective view of the invention with the tablet's stand in the open position; and,

FIG. 11 is a top perspective view of the invention in use displaying a plurality of holograms with the tablet's stand in the open position.

The dotted lines in FIG. 11 showing an exemplary plurality of holographic images are for illustrative purposes only, forming no part of the claimed design.
